The ornamental design for an upper portion of a bottle, as shown and described.

DESCRIPTION

FIG. 1 is a perspective view of an upper portion of a bottle, embodying our new design;

FIG. 2 is a top view thereof;

FIG. 3 is a front elevational view thereof;

FIG. 4 is a side elevational view thereof, the opposite side elevational view thereof being a mirror image; and,

FIG. 5 is a rear elevational view thereof.

The broken lines shown in the figures are for illustrative purposes only, and form no part of the claimed invention.
